FIG. 1 is a perspective view of a slide room for a recreational vehicle, showing the slide room installed in a recreational vehicle and positioned in a partially extended position, the slide room having a fiberglass end wall and integral flange. FIG. 2 is a perspective view of the recreational vehicle and slide room of FIG. 1 showing the slide room in a fully retracted position.

FIG. 3 is a side elevation view of the recreational vehicle and slide room of FIG. 1.

FIG. 4 is a bottom plan view of the recreational vehicle and slide room of FIG. 1 showing the slide room in the partially extended position; and,

FIG. 5 is a front elevation view of the recreational vehicle and slide room of FIG. 1 showing the slide room in the partially extended position.

The long-dash short-dash lines in FIGS. 1-3 are boundary lines indicating the bounds of the claimed subject matter. All other portions of the slide room and recreational vehicle shown broken lines throughout the drawings are for illustrative purposes and form no part of the claimed design.
